UNITED STATES PATENT OFFICE.

ALBERT ROMAINE TALLMAN, OF NASHVILLE, TENNESSEE.

GAS COCK.

Application filed February 9, 1921. Serial No. 443,596.

To all whom it may concern:

Be it known that I, ALBERT R. TALLMAN, a citizen of the United States, residing at Nashville, in the county of Davidson and 5 State of Tennessee, have invented a new and useful Gas Cock, of which the following is a specification.

The device forming the subject matter of this application is a cock, which may be used 10 on gas lines, although the cock, obviously, may be used to control the flow of fluid of any kind.

The invention aims to provide means whereby a rotation of the valve of the cock 15 will be rendered somewhat difficult, to the end that the valve cannot be tampered with or closed readily, the construction being such, withal, that the valve may be rotated readily, at the hand of a person having a 20 properly constructed wrench or key.

It is within the province of the disclosure to improve generally and to enhance the utility of devices of that type to which the invention appertains.

25 I do not bind myself to the specific form depicted and described, since, within the scope of what is claimed, a mechanic may work changes, without departing from the spirit of the invention.

30 In the drawing:—Figure 1 shows in top plan, a device constructed in accordance with the invention, the cap portion of the casing having been removed; Figure 2 is a like view wherein the cap appears as an added 35 dep-

tail; Figure 3 is a side elevation, the cap being in section; Figure 4 is a section on the line 4—4 of Figure 1; Figure 5 is a perspective view of the wrench or key.

40 The numeral 1 denotes a casing comprising a body 2 having a neck 3 provided with a notch 4 defining shoulders 5. A valve is journaled in the body 2 and controls the passage of fluid through the casing. The valve comprises a tapered main member 6 having a stem 7 whereon a nut 8 is threaded, a washer 9 being interposed between the nut and the body 2 of the valve casing.

45 The nut 8 and the washer 9 are of conical form, and for that reason, it will be 50 practically impossible to apply a tool to the lower end of the valve and rotate the valve. The main member 6 of the valve has a lateral projection 10 which cooperates with the shoulders 5 to stop the valve in an open position and in a closed position. A trough-shaped shell 11 projects from the end of the

valve body 6 and is provided at its edges with inwardly extended ribs 12.

There is a seat 14 in the end of the valve member 6. A spindle 15 is carried by the 60 member 6 and extends through the seat 14. A cover plate 16 is mounted to slide on the spindle 15 and has a reduced extension 17 enlarged as at 18 to engage with the ribs 12, the construction being such that the cover 65 plate is held by the fin or shell 11, for rotation with the valve. The cover plate 16 has outwardly projecting lugs 19. A compression spring 20 surrounds the spindle 15, one end of the spring being received in the 70 seat 14, the other end of the spring engaging the cover plate 16.

A cap 21 surrounds the neck 3 and is held thereon by one or more securing elements 22. The cap may be considered as a part 75 of the casing 1. In the end of the cap 21 there is an opening or key hole 23 having a lateral extension 24. The plate 16 forms a closure for the key hole 23 and is pressed against the end of the cap by the spring 20. 80 The lugs 19 on the cover plate 16 engage the end of the cap and space the cover plate far enough from the end of the cap so that the cover plate is engaged by the fin or shell 11, for rotation with the valve. The num- 85

meral 25 marks a wrench or key including a shank 26 and a handle 27. There is an opening 28 in the end of the shank 26, the shank having a lateral bit 29. The spindle 15 is aligned with the key 90 hole 23 and when the spindle is received in the opening 28 of the key 25, the bit 29 passes through the extension 24, the cover plate 16 being pressed inwardly and the spring 20 being compressed. When the key 95 25 is rotated, the bit 29 engages one or the other of the ribs 12 at the ends of the fin or shell 11 on the valve, rotation being imparted thus to the valve. When the key 25 is withdrawn, the cover plate 16 assumes the 100 position of Figure 4, and, since the cover plate is assembled with the valve, for rotation therewith, it will be obvious that an unauthorized rotation of the valve will be rendered difficult.

105 I claim:—

1. In a device of the class described, a casing having a key hole; a valve journaled in the casing and provided with a fin; a spindle on the valve and aligned with the 110 key hole; a cover plate for the key hole, the cover plate being slidable on the spindle

and being interengaged with the fin against the rotation independently of the valve, the plate having lugs engaging the casing to hold the cover plate engaged with the fin; and a spring on the spindle and interposed between the valve and the cover plate.

2. In a device of the class described, a casing having a key hole; a valve journaled in the casing and provided with a fin; a spindle on the valve and alined with the

key hole; a cover plate for the key hole, the cover plate being slidale on the spindle and being interengaged with the fin for rotation with the valve; and a spring on the spindle and interposed between the valve and the cover plate.

In testimony that I claim the foregoing as my own, I have hereto affixed my signature.

ALBERT ROMAINE TALLMAN.
